(57) **CLAIM**

We claim the ornamental design for a multi-piece fruit snack, as shown and described.

DESCRIPTION

FIG. 1 is a perspective view of an exemplary embodiment of the invention having four intertwined strands including three outer strands and a center strand;

FIG. 2 is a fragmented elevational view of thereof;

FIG. 3 is an end view thereof;

FIG. 4 is a perspective view of a second embodiment of the invention;

FIG. 5 is a perspective view of a third embodiment of the invention;

FIG. 6 is a perspective view of a fourth embodiment of the invention;

FIG. 7 is a perspective view of a fifth embodiment of the invention; and,

FIG. 8 is a perspective view of a sixth embodiment of the invention.

The multi-piece fruit snack is useful for consumption. The disclosed embodiments of the invention demonstrate that individual strands can define different flavorings, colorings, and textures. The disclosed embodiments of the invention also demonstrate that any combination of strands having different flavorings, colorings, and textures can be joined to practice the invention.
